UNITED STATES PATENT OFFICE.

CHARLES W. BECK, OF ROCKVILLE CENTER, NEW YORK, ASSIGNOR, BY MESNE ASSIGNMENTS, TO MICHIGAN MOTOR SPECIALTIES COMPANY, OF DETROIT, MICHIGAN, A CORPORATION OF MICHIGAN.

SPARK-PLUG.

1,093,598.

Specification of Letters Patent. Patented Apr. 21, 1914.

Application filed March 17, 1910. Serial No. 549,873.

To all whom it may concern:

Be it known that I, CHARLES W. BECK, a citizen of the United States, and resident of Rockville Center, county of Nassau, and 5 State of New York, have invented certain new and useful Improvements in Spark-Plugs, of which the following is a specification.

Spark plugs in which the core is made of 10 a sheet of mica rolled lengthwise or longitudinally of the core are objectionable for the reason that the rolled mica sheet flakes, that is, breaks off in minute particles in the engine cylinder. These flakes or particles 15 become red hot and frequently cause premature explosions in the cylinder. A spark plug having a mica core so formed is much cheaper than a core made up of small disks of mica secured to the central electrode, and 20 for that reason are used, notwithstanding the very great objection to them just mentioned.

It is one of the main objects of this invention to provide a spark plug having a 25 rolled mica core with means to prevent the flaking of the mica within the engine cylinder.

Another important object of the invention 30 is to provide means whereby the inner portion of the base of the plug on the inner end of the insulator will be protected from the carbon deposit caused by the vaporization and burning of the oil within the cylinder.

In the drawings, Figure 1 is a longitudinal 35 vertical sectional view of the plug complete; Fig. 2 a horizontal sectional view on the line II—II of Fig. 1; Fig. 3 a perspective view of the protecting firing sleeve removed; and Fig. 4 a view of the inner end 40 of the plug.

Referring to the various parts by numerals, 1 designates the plug base which is threaded to adapt it to be screwed into the engine cylinder. Screwed into the outer 45 end of this base is the core securing gland 2. The core 3 is formed of sheet mica rolled, the folds or layers of the mica extending longitudinally of the core. This core is tapered longitudinally from a point 3^a near its 50 inner end to its outer end, and the interior of the core securing gland is correspondingly tapered, and the core forced into it by com-

pression so that said gland will rigidly hold the core in position in the base and prevent its outward withdrawal therefrom. Extending longitudinally through the core 55 is the central or insulated electrode 4, said electrode being provided near its inner end with a collar 5 which rests within a recess 6 formed at the inner end of the core. The 60 outer end of the core, that is to say, that portion which projects outwardly beyond the securing gland, is covered and protected by means of a cap 7, said cap preferably being formed of porcelain. It will, of course, be 65 understood, however, that this cap may be formed of any suitable insulating material. The outer end of the central or insulated electrode is threaded to receive a binding 70 nut 8, which serves to hold the porcelain cap in position and also as a means for securing the electrode in the core, and as a connecting device for the terminal wire. A washer 9, preferably of asbestos, is interposed between the inner end of the protecting cap and the 75 outer surface of the securing gland so that the pressure of the nut 8 will not fracture the cap. As shown in Fig. 1, the mica core terminates slightly below the upper end of the 80 cap in order to leave a slight space between the core and the cap, thereby permitting the cap to be firmly clamped against the washer 9, and also leaving room for a variable expansion between the core and the cap. 85

The inner end of the mica core, that is to say, that portion extending inwardly beyond the securing gland and inclosed within the base, is preferably cylindrical. It will, of course, be understood, however, that 90 it may be of any desired shape. Fitting over and protecting this end of the core is a cap 10 of suitable insulating material, preferably of porcelain. This cap is slightly longer than the inner end of the core to 95 provide the space 11 between said cap and the inner end of the core to allow for the unequal expansion of the cap and the core. The cap is secured in position by means of a nut 12 screwed on the electrode and bearing against the inner end of said cap, a washer 13, preferably of asbestos, being interposed between the end of the cap and the inner end of the securing gland. The nut 100

12 is provided with flexible spider arms 14, which are adapted to bear against the end of the porcelain cap and serve to prevent the nut fracturing the cap, and also to permit of an unequal expansion between the cap and the electrode.

Fitting within the base is a removable metallic firing cap 15, said cap being provided with a projection 16 on its outer surface adapted to snap into an internal annular groove in the base, said groove being near the inner end of the base. By this means the cap will be removably, but rotatably held within the base. This cap is formed with an enlargement at its inner end, that is to say, the end extending into the engine cylinder, said enlargement forming a shoulder 17 adapted to abut against the inner edge of the base, and the inner end of the cap is closed by a wall 18, said wall being formed with an opening 19 eccentric to the axis of the cap. Around the edges of this opening is secured an eyelet of non-corroding metal 20 of high conductivity. The end of the insulated electrode projects through this opening, and of course, is eccentric to said opening, being centrally disposed within the cap. It will, therefore, be seen that the electrode is nearer one point on the margin of the eyelet than it is to all the other points on said margin. The spark will jump from said electrode to the eyelet. The firing cap closes the inner end of the base of the plug with the exception of the small opening 19. By this means the deposit of carbon within the base and on the insulator or core is largely prevented.

From the foregoing it is manifest that I provide an inexpensive spark plug which will be very durable, and wherein a rolled mica core may be employed without any danger of the mica flaking off within the cylinder. It is also manifest that by reason of the efficient protection which I provide for the core, said core will be practically indestructible. By reason of the removable firing cap, and the removable insulating cap for the inner end of the core, the plug may be readily cleaned. These two parts will receive all of the soot accumulation, and by removing them and replacing clean parts, the plug may be at once replaced in the cylinder in good working condition. The removable parts may be cleaned at leisure or entirely discarded if they are at all worn or injured. By rotating the cap in the plug a fresh sparking point may be brought into sparking relation with the electrode. By providing the plug with the annular groove so that the retaining projection 16 may enter said groove at any point, the cap may be readily placed in the plug and any point on the margin of the eyelet 17 may be brought into sparking relation with the electrode.

Having thus fully described my invention,

what I claim as new and desire to secure by Letters Patent is:

1. A spark plug comprising a base, a rolled mica core secured within said base, a porcelain cap inclosing the inner end of said core and protecting it from the engine gases, an electrode extending through said core and said cap, and means on the electrode engaging the end of the cap for yieldingly securing said cap in place. 75

2. A spark plug comprising a base, an insulating core secured in said base, a cap inclosing the inner end of said core, an electrode extending through the core and said cap, and yielding means on the electrode and engaging the cap for securing said cap in place. 80

3. A spark plug comprising a base, an insulating core secured in said base, a porcelain cap inclosing the inner end of said core, an electrode extending through the core and said cap, a nut screwed on the inner end of said electrode and carrying yielding fingers or spider arms adapted to bear against the inner end of the cap for yieldingly holding 90 said cap in place. 85

4. A spark plug comprising a base, a rolled sheet mica core extending through said base, said core being tapered outwardly, an electrode extending through said core, a porcelain protecting cap within the base and inclosing the mica core, a washer between the end of said cap and the base, a porcelain cap inclosing the outer end of the core, a washer between the inner end of said cap 100 and the outer surface of the base, the electrode extending through both of said protecting caps, a clamp nut threaded on the outer end of said electrode, means on the electrode for engaging the inner end of the 105 mica core, and means on the electrode for engaging the inner end of the inner protecting cap, whereby the core will be wedged in the base and the protecting caps will be held rigidly against the base. 110

5. A spark plug comprising a base, a rolled sheet mica core tapered outwardly and fitting in said base, an electrode extending through said core, a protecting cap surrounding the inner end of said core, means on the electrode to engage the inner end of the core within the cap, means on the electrode to engage the protecting cap and means on the outer end of the electrode for drawing said electrode outwardly and thereby wedging the core in the base and holding the protecting cap tightly over the inner end of the core. 115 120

6. A spark plug comprising a base, an electrode extending through said base, a removable cylindrical cap fitting within the inner end of the base and covering the entire cylindrical inner surface thereof, said cap being detachably held therein by reason of its elasticity and being closed outside of 125 130

the base except for an opening in its end eccentric to the electrode and through which the electrode extends, whereby the spark will be formed between the electrode and the 5 margin of the said opening.

7. A spark plug comprising a base, a rolled sheet mica core supported approximately midway between its ends by said base, the folds or layers of said mica sheet 10 extending longitudinally of the core, an electrode extending longitudinally through the center of said core, a cap of insulating material inclosing each of the projecting ends of the core, the inner ends of said caps 15 bearing against the core support and the outer ends of said caps being closed except where the electrode passes through them, the interior of each of said caps being larger than the inclosed portion of the core, where- 20 by there is a space within said cap to permit of an unequal expansion and contraction of the core and caps, and means for securing the caps in place.

8. A spark plug comprising a base, a core 25 tapered outwardly and fitting in said base, an electrode extending through said core, a protecting cap of insulating material surrounding the inner end of said core, means

on the electrode to engage the inner end of the core within the cap, means on the electrode to engage the protecting cap, and means on the outer end of the electrode for drawing said electrode outwardly and thereby wedging the core in the base and holding the protecting cap over the inner end of the 30 35 core.

9. A spark plug comprising a base, an electrode extending through said base, a removable and freely rotatable cylindrical cap fitting within the inner end of the base and 40 covering the entire inner surface thereof, means for detachably and rotatably holding said cap in the base, the inner end of the cap being provided with an aperture eccentrically located with respect to the electrode, 45 the margin of said aperture being at one point close to the electrode, whereby upon rotating the cap said point may be brought close to different points on the electrode.

In testimony whereof I hereunto affix my 50 signature in the presence of two witnesses this 16th day of March 1910.

CHARLES W. BECK.
